UNITED STATES PATENT OFFICE

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY

SELF-CONTAINED MECHANICAL REFRIGERATOR

Application filed August 3, 1926. Serial No. 126,781.

This invention relates to the transforming of heat by mechanical means and more specifically to self-contained outfits, usually in cabinet form, for producing refrigerating effects.

The combining of a refrigerating plant with a cabinet to form a self-contained mechanical refrigerator is well known. Known types utilize for a working substance a low-boiling high-pressure liquid, such for example as sulphur dioxide or methyl chloride. In these refrigerators it is common practice to combine the four principal elements, namely, motor, compressor, condenser, and evaporator so that all may be removed as a unit in order that they may be put into or taken from the cabinet as a unit by the service man without the necessity of disconnecting any part containing the high pressure liquid, thereby to avoid the well known dangers, delays and expense of servicing such apparatus on the user's premises. It is obvious, however, that while the dangers attending the opening up of a high-pressure system in the user's home are avoided by such means, compensating disadvantages result from the difficulty of removing and transporting to the shop these great heavy plants comprising motors, pumps, condensers, evaporators, fans, switches, base plates, etc., and it is the more wasteful because in a very large percentage of the cases, probably ninety-nine out of a hundred, only the moving parts will actually be worked upon in the shop.

One object of the invention is to develop an improved type of self-contained refrigerating outfit. Another object is to provide apparatus from which the parts requiring servicing can be quickly and safely removed and easily transported without disturbing any parts not requiring servicing. Another object is to device an improved combination of cabinet and refrigerating plant permitting a novel arrangement of the apparatus parts and a complete segregation of the moving parts from the non-moving parts. Other objects will be apparent from the detailed description which follows.

Instead of first combining into one plant all or most of the mechanical, controlling, and

heat transforming elements and then combining this in turn with the cabinet as has previously been done in many ways, the present invention contemplates combining with the food cabinet the heat transferring elements 55 comprising the condenser and the evaporator which are built into the cabinet, so to speak, while the moving parts consisting essentially of a motor and a pump with necessary controls may form a separate unit. 60 The condenser is preferably arranged to be air cooled but no fan or other mechanically driven air-agitating or other draft inducing means are provided. The connections between the pump or compressor and the evaporator and condenser are readily separable to permit the convenient substitution upon the premises of a new motor-pump unit in case of failure of the old. Opening of the system can be effected without danger since the invention is designed to apply to systems utilizing as working substances harmless, low-pressure, high-boiling liquids operating in accordance with the process disclosed in my copending application, Serial No. 15,172, 75 filed March 12, 1925. The invention further comprises suitable means for deflecting from the cabinet the heat given up by the condenser, and for protecting the condenser element against damage. 80

In order to illustrate the invention, one concrete embodiment thereof is shown in the accompanying drawings, in which:

Fig. 1 is a vertical sectional view of a refrigerating cabinet substantially on the line 1-1 of Fig. 2;

Fig. 2 is a rear end elevational view of the cabinet shown in Fig. 1.

Fig. 3 is a fragmentary sectional view on an enlarged scale substantially on the line 3-3 of Fig. 2.

The embodiment of the invention chosen for the purpose of illustration comprises a cabinet A of any suitable or desired type having walls insulated against the passage of heat which may be arranged for the preservation of perishable articles, the freezing of liquids, or both. Secured within the cabinet is an evaporator element 3, such as a coil of pipe disposed adjacent the cabinet wall. 100

Upon the exterior of the cabinet is disposed a condenser element 4. For convenience and to permit short connections, the evaporator and condenser elements may be on opposite sides of the same wall of the box, such as its back as indicated. A connection 5 leads from the bottom of the condenser to the bottom of evaporator 3, a suitable feeding device or expansion member 6 forming a part 10 of the connection. A connection 7 indicated in part diagrammatically by a single line for the sake of clearness, leads from the top of evaporator 3 and a similar connection 8 leads from the top of condenser 4. Connections 7 and 8 terminate in separable couplings or connections 7' and 8' respectively for convenient attachment to a pump or compressor such as 9, which, together with its operating motor 10, may be structurally united to 20 form a small, compact, and light motor-pump unit, particularly when the pump is of the rotary type. Connection 7 is arranged to lead to the inlet of the pump and connection 8 to its outlet so that the evaporator, pump and condenser are connected together to form 25 a closed cycle system. Motor pump unit 10, 9 is shown disposed beneath the cabinet A, but it may be disposed at any other convenient point.

30 The refrigerating plant is arranged to operate on the vapor-gas principle disclosed in my copending application Serial No. 15,172, filed March 12, 1925 and utilize a lubricating working substance such as disclosed 35 in my copending application Serial No. 60,311 filed October 3, 1925 in accordance with the processes disclosed in my copending applications Serial No. 85,580 filed February 2, 1926 and Serial Nos. 106,825 and 40 106,826 filed May 5, 1926. A typical working substance of the described type is composed of methylene chloride 85% and a grease such as vaseline 15%. To properly concentrate such a working substance, the 45 pump preferably operates at a fairly high temperature in order that the volatile component of the working substance may be driven off. Hence, cooling of the pump is intentionally limited and no cooling means whatever are provided for it.

Condenser 4 is constructed and arranged to produce adequate cooling of the circulated working substance by natural draft. To this 50 end condenser 4 is disposed in spaced relation to the wall of the cabinet and presents an extended surface as by the use of flattened or finned tubing which is found to give very satisfactory results with a column of air passing at low velocity such as is induced by vertically disposing the condenser and discharging the products of pump 9 at their greatest temperature into the top of the condenser. A considerable part of the heat is 55 found to dissipate by radiation while the re-

mainder of the heat which is given up passes away by convection. The size of such a condenser is entirely practical and in most instances need not cover much more than a third of one side of the cabinet.

With no fan or other air agitating means needed to cool either condenser 4 or pump 6, it is obvious that there is no cooperation between the motor and the condenser or the pump for cooling purposes. Hence, the motor-pump unit may be at any convenient remote point from the other elements of the system. As this unit contains all the moving parts of the system and the only ones ordinarily requiring servicing, the evaporator and condenser are built into and form a substantially permanent part of the refrigerator cabinet.

Since condenser 4 gives off much heat by radiation, it is desirable to deflect the same away from cabinet A. This may be accomplished by making the insulated wall between the evaporator and the condenser of extra thickness or alternatively or additionally by providing intermediate the condenser and the wall a deflecting member which may take the form of a plate 11 which is spaced from both the wall and the condenser. This plate may be of any suitable or desired material but since it is intended to deflect radiated heat it preferably is of some metal which presents a reflecting surface such, for example, as tin.

Suitable means are provided for protecting the condenser element 4 against damage. Such means may comprise side extensions *a* on cabinet A projecting beyond condenser 4, the intervening space between extensions *a* may be spanned by some form of suitable reticulated material 12, such as wire netting. One or more bridge pieces 13 of metal or other suitable material may support the netting 12 intermediate extensions *a*. I am aware that condensers have heretofore been incased to form so-called flues in order better to direct the cooling medium upon the condenser. No such flue arrangement is required with my condenser which functions perfectly in the open air. The side extensions and the reticulated material are for protection only and can be dispensed with entirely if not needed or desired so long as the atmosphere has free access to the condenser.

While a preferred form of the invention has been herein shown and described, it is to be understood that the invention is not limited to the specific details thereof, but covers all changes, modifications, and adaptations within the scope of the appended claims.

I claim as my invention:

1. A refrigerator cabinet having an insulated wall, an evaporator element upon one side of said wall, a condenser element upon the other side of said wall, and means interposed between said condenser element

and said wall for reflecting the heat of said last named element.

2. A refrigerator cabinet having an insulated wall, an evaporator element upon one side of said wall, a condenser element upon the other side of said wall, and a reflecting plate between said condenser element and said wall.

10 3. A refrigerator cabinet having an insulated wall, an evaporator element upon one side of said wall, a condenser element upon the other side of said wall, and a heat reflecting member between said condenser element and said wall and in spaced relation to both.

15 Signed by me at Detroit, Wayne County, Michigan, this 31st day of July 1926.

RANSOM W. DAVENPORT.
